UNITED STATES PATENT OFFICE.

WILLIAM L. MCGRATH, OF ELMIRA, NEW YORK, ASSIGNOR TO ECLIPSE MACHINE COMPANY, OF ELMIRA, NEW YORK, A CORPORATION OF NEW YORK.

ENGINE-STARTER.

1,351,860.

Specification of Letters Patent.

Patented Sept. 7, 1920.

Application filed March 20, 1919. Serial No. 283,777.

To all whom it may concern:

Be it known that I, WILLIAM L. MCGRATH, a citizen of the United States, residing at Elmira, in the county of Chemung and State of New York, have invented certain new and useful Improvements in Engine-Starters, of which the following is a specification.

My invention relates to the drive or transmission portion of an engine starter, and the object thereof is to provide a simple, efficient and reliable construction of drive more particularly adapted for hand operation as distinguished from power operation through a starting motor, although such construction is capable of operation by either hand or power. The various features of advantage and utility in the construction and operation of my form of drive will be apparent from the description hereinafter given.

In the drawings Figure 1 is an elevation partly in section of a drive embodying my invention, Fig. 2 an end elevation thereof, and Figs. 3 and 4 sections on the same line 25 of Fig. 1 but looking in opposite directions as indicated by the corresponding numerals.

Referring to the particular embodiment of my invention as herein shown, the drive consists of a suitably supported or journaled 30 rotatable member or shaft 1, and a driving gear 2 adapted to engage and drive a rotatable part of the engine to be started such as the fly wheel 3 thereof.

In the present instance the shaft is driven 35 by a driving wheel which is here in the form of a sprocket wheel 4 secured to one end of said shaft in suitable manner as by means of the key 5 and cross pin 6. In practice this wheel, and of course the drive, is adapted to be driven by hand, that is to say, the engine is adapted to be hand cranked through the mechanism now being described and, as shown, the sprocket wheel 4 is itself driven by another sprocket wheel 7 through 45 the medium of a chain 8, said wheel 7 being secured to a rotatable shaft 9 adapted to be connected either directly or indirectly with a hand crank (not shown).

The rotatable shaft has a screw threaded 50 portion 1^a on which is screw threaded the gear 2 whereby such gear is capable of automatic longitudinal movement in going into and out of mesh with the fly wheel and is also capable of rotary movement with the 55 shaft at the end of its inward longitudinal

movement for meshing purposes. The shaft is provided toward its central portion with clutch jaws 10 adapted to cooperate with corresponding rightangled clutch jaws 11 whereby the gear will partake of the rotary 60 movement of the shaft when the clutch jaws are in engagement during the operation of driving the fly wheel.

The outer face of the gear 2 is provided with a hub 12 having a substantially semi-circular extension 12^a which is adapted to cooperate with a pin 13 anchored in one end of the shaft and projecting radially therefrom so as to be contacted by an edge of the semi-circular hub portion 12^a and also co-operating with a retainer which is in the form of a flat spring 14 secured to such hub. This spring is preferably of the form illustrated in Fig. 2, wherein the same is anchored at one end to the hub as by means of 75 the screws or rivets 15 and having intermediate its length an upwardly curved portion 14^a raised above the hub and an inwardly extending portion 14^b resting with a yielding pressure upon said hub. By reason of this raised portion the gear is permitted a freedom of rotative movement to a limited extent but is prevented from rotating except through the exercise of positive power intentionally applied, whereupon the pin 13 would be rotated relative to the retainer 14 and the gear will thereupon 80 be permitted to be advanced longitudinally for meshing purposes.

The particular object of this retainer is to guard against the 90 possibility of accident especially when the drive is hand-cranked and the cranking is inadvertently being continued at the time of a back fire of the engine, in which event the pinion might be again meshed with the rotating fly wheel, with possible damage to the mechanism and injury to the operator. It is evident that by the use of my retainer the gear 2 will under such conditions be held or retained in its normal or disengaged position and will rotate with the shaft if the cranking is continued. By a quick or snappy initial movement of the hand-crank and shaft the gear is disengaged from the retainer by having the pin 13 pass the spring 95 portion 14^b of the retainer.

In case the teeth of the gear 2 should abut the teeth of the fly wheel 3 end to end, provision is made for the slight rotary movement of such gear by the operator, such 110

means being placed within ready reach of the operator's hand or foot, preferably the latter. As shown in Figs. 1 and 2 such means consists of a manually or pedally operated plunger 16 adapted to reciprocate in a casing or sleeve 17 which is suitably mounted in a support or bracket 18, itself mounted in fixed relationship to the engine or more particularly the drive or transmission. This plunger is located directly above or in the plane of the gear 2 and is adapted to enter between two adjacent teeth of the gear with its pointed lower end 16a. This pointed or inclined end of the plunger is adapted to bear against the curved side of one or the other of said two adjacent teeth and to thereby slightly rotate the gear in one direction or the other sufficiently to bring the gear teeth and fly wheel teeth into register and permit the desired meshing thereof upon the continued rotation of the screw shaft. This plunger 16 is retracted to normal position after its operation by means of the coil spring 19.

25 It will be understood that this plunger is also useful to prevent rotation of the pinion at the time when it should advance longitudinally, inasmuch as the projection of this plunger between the pinion teeth locks it 30 against rotation and assures meshing with the engine member.

The gear teeth are of the peculiar form shown in order to facilitate meshing by being cut away at their engaging end, thereby presenting a minimum of surface for end contact and permitting meshing at the widest portion of the angular space between the fly wheel teeth. This feature is not herein claimed but made the subject matter 40 of a separate application.

It will be understood that when I use the term "manual" as applied to the operation of the plunger I mean to include both the manual and pedal operation thereof.

45 I claim:

1. In a device of the class described, the combination of a rotatable shaft, a driving member mounted thereon for longitudinal movement thereof and rotary movement therewith, and means for yieldingly holding such member in normal position on the shaft but permitting a limited free rotary movement thereon such means comprising a projection on the shaft and a spring anchored 50 at one end to the driving member with its intermediate portion arched to extend over such projection.

2. In a device of the class described, the combination of a rotatable shaft, a driving member mounted thereon for longitudinal movement thereof and rotary movement therewith, and coöperating elements mounted on said member and shaft respectively and arranged to permit a limited free rotary movement of the shaft with respect to

said member but tending to yieldingly hold such member into rotatorial engagement with the shaft, except when the shaft is rotated with a sudden snappy action.

3. In a device of the class described, the combination of a rotatable shaft, a driving member mounted thereon for longitudinal movement thereof and rotary movement therewith, and coöperating members mounted on said member and shaft for yieldingly holding such member in normal position on the shaft but permitting a limited free rotary movement theron, such means comprising a projection on the shaft and a curved spring mounted on such member and normally inclosing and coöperating with the projection.

4. In a device of the class described, the combination of a rotatable shaft, a driving member mounted thereon for longitudinal movement thereof and rotary movement therewith, and coöperating members mounted on said member and shaft for yieldingly holding such member in normal position on the shaft but permitting limited free rotary movement thereon, such means comprising a projection on the shaft and a curved spring mounted on such member and coöperating with the projection, such member having a stop shoulder coöperating with the projection to stop the same in its return longitudinal movement.

5. In a device of the class described, the combination of a rotatable shaft, a gear mounted thereon for longitudinal movement thereof and rotary movement therewith and having a hub, a radial projection on the shaft, and yielding means mounted on the hub and coöperating with the projection to engage the same to yieldingly hold it in normal position on the shaft, but permit a limited free rotary movement thereon.

6. In a device of the class described, the combination of a rotatable shaft, a gear mounted thereon for longitudinal movement thereof and rotary movement therewith and having a hub, a radial projection on the shaft, and yielding means mounted on the hub and coöperating with said projection to engage the same to yieldingly hold the gear in normal position on the shaft, but to permit a limited free rotary movement thereof on the shaft, such means comprising a spring connected at one end to the hub with its other or free end bearing against such hub and with an intermediate portion outwardly extended to receive the projection when the gear is in normal position.

7. In a device of the class described, the combination of a rotatable shaft, a gear mounted thereon for longitudinal movement thereof and rotary movement therewith and having a hub, a radial projection on the shaft, and yielding means mounted on the hub and coöperating with said projection to

engage the same to yieldingly hold the gear in normal position on the shaft, but to permit a limited free rotary movement thereof on the shaft, said hub having a projecting portion adapted to engage said shaft projection to stop the return movement of the gear on the shaft.

8. In a device of the class described, the combination of a rotatable shaft, a gear mounted thereon for longitudinal movement thereof and rotary movement therewith and having a hub, a radial projection on the

shaft, and yielding means mounted on the hub and coöperating with said projection to engage the same to yieldingly hold the gear in normal position on the shaft, but to permit a limited free rotary movement thereof on the shaft, said hub having a laterally extending portion providing a shoulder adapted to contact said shaft projection at the end of the return movement of the gear on the shaft.

WILLIAM L. McGRATH.
